UNITED STATES PATENT OFFICE.

ELVA BOWMAN, OF FORT WAYNE, INDIANA.

CHIROPRACTIC TABLE.

Application filed June 23, 1921. Serial No. 479,751.

To all whom it may concern:

Be it known that I, ELVA BOWMAN, a subject of the King of Great Britain, and resident of Fort Wayne, in the county of Allen 5 and State of Indiana, have invented certain new and useful Improvements in Chiropractic Tables, of which the following is a specification.

This invention relates to improvements in 10 chiropractic tables and the object thereof is to afford a construction having adjustable knee, head and abdominal supports and also a tilting sternum rest and in which the sustaining means for the abdominal supports 15 will afford decreasing resistance as the abdominal supports are depressed. And, another object is to provide means in connection with the forward abdominal support for elevating the sternum when in its upper- 20 most normal position.

These objects are accomplished by the construction illustrated in the accompanying drawings in which:—

Fig. 1 is a side elevation of the table embodying the invention, parts thereof being 25 in section;

Fig. 2 is a plan view of a portion of the table including the knee rest and the abdominal supporting pads, there being a portion broken away; and

Fig. 3 is a front end elevation of the table.

Similar characters of reference indicate corresponding parts throughout the several views and having reference now to the 35 same:—

The table has for its frame a foot pedestal 1 and a head pedestal 2 which are spaced apart and connected together by side rails 3. Upon the upper end of the foremost legs 4 of 40 the pedestal 1 is pivoted a frame 5, and upon the frame is mounted a knee-rest 6 adapted to have longitudinal sliding movement thereon. A lever 7 is pivoted at its forward end to the frame and has a bolt 8 that extends through the side of the frame and engages in one or the other of a series of holes 9 in the side of the knee-rest to thus lock the knee-rest in adjusted positions accordingly. The rear end of the frame 5 has hinged 45 thereto a prop 10, the lower end of which has a cleat 11 fixed thereto adapted to rest upon a supporting cleat 12 that is fixed in the foot pedestal so as to support the frame in elevated position. A spring 13 acts against

the inner face of the prop to hold it in engagement with the supporting cleat. 55

A horizontal shelf 14 has hinged connection at its rear end, as indicated by 15, in the rear upper part of the foot pedestal and projects forwardly beyond the forward end 60 of the knee-rest 6 and has mounted thereon a pair of pads 16 for the support of the pelvic region of the patient. A prop 17 is hinged at its upper end to the underside of the shelf 14 and is connected at its lower end with a 65 stirrup 18, the upper ends of which are pivotally connected in the foot pedestal.

A toggle mechanism comprised of an arm 19 and crank 20 is arranged in connection with the prop 17, the connecting bar 19 being hinged at its forward end to the prop, and the crank being mounted in a bracket 21 that is secured to the underside of the shelf 14 near its rear end. A pair of tension springs 22 are connected at their opposite ends with corresponding cross-bars 23 and 24, the cross-bar 23 being connected with the rear end of the toggle arm 19, and the bar 24 being connected with an adjusting lever 25 by means of a rod 26. The 70 lever 25 is secured in adjusted positions by means of a hook 27 which is arranged for connection with screw eyes 28 on the under side of the shelf 14. 75

A lock bar 29 is hinged at its rear end in 80 connection with the pedestal 1, its forward end being adapted to be drawn upward so as to engage the lower end of the prop 17 and prevent movement thereof. The lock bar is actuated by a lever 30 that is pivoted 85 on one side of the shelf 14 and which has connection with the lock bar through the medium of a cable 31 and coil spring 32.

Upon the upper end of the head pedestal 2, at the rear thereof is a cross piece 33 90 upon which is hinged a tilting sternum rest 34, the rear portion of which rests upon studs 35 that project upwardly from the shelf 14 and extend loosely through the cross piece 32.

A frame 36 is hinged at its rear end to the cross piece 33 and is supported at its forward end upon a prop 37 that has adjustable supporting connection at its lower end with cleats 38 in the head pedestal, 100 there being a cleat 39 on the prop for engaging the cleats 38. A spring 40 bears 105 against the inner face of the prop 37 and

acts to hold the prop in engaging position. The frame 36 has longitudinally disposed side bars 41 that are spaced apart and a pair of face rests 42 are hinged respectively upon the side bars at the inner edges thereof so that each of the rests may be tilted upon a longitudinal axis. A crank rod 43 mounted in the frame acts to sustain the rests in horizontal position when the crank 10 is turned upwardly so as to engage and support the inner edges of the rests. The outer end of the crank rod is bent so as to form a handle 44 by which the rod may be turned.

15 In the forward upper portion of the head pedestal 2 is hinged a shelf 14' that extends rearwardly from its hinge 15' substantially in the plane of the shelf 14 in the foot pedestal, and has mounted upon its rear end 20 a rest 16' for the support of the abdomen. The shelf 14' is yieldingly sustained in its uppermost position by a mechanism similar to that provided for the shelf 14 in the foot pedestal, the mechanism consisting of a prop 25 17', stirrup 18', toggle arm 19', crank 20', bracket 21' attached to the shelf, springs 22' connected at their respective ends with cross bars 23' and 24', and an adjusting lever 25' connected with the cross bar 24', the various parts being arranged in connection with each other as in the former instance. Also, 30 a lock-bar 29' is provided for engagement with the lower end of the prop 17' and arranged to be controlled by a lever 30' through the medium of a cable 31', and spring 32'.

In using the invention, the knee rest 6 is adjusted longitudinally on its frame to suit the stature of the patient to be treated, 40 and the patient is positioned with the pelvic and abdominal region resting upon the pads 16 and 16', and the face resting upon the pads 42, which may be accommodately tilted so as to conform with the angularity 45 of the face of the patient, by manipulating the crank rod handle 44. By manipulating the levers 30 and 30' so as to relieve the tension of the springs 32 and 32', the corresponding lock bars 29 and 29' drop from 50 engagement with the props 17 and 17' so that the shelves 14 and 14' may be depressed to an extent dependent upon the weight applied to the back of the patient in the customary manner.

55 A feature of the invention is that the sustaining mechanism for the shelves affords yielding support therefor and with decreasing resistance as the shelves are progressed downwardly. Ordinarily, in apparatus of 60 this class the tension mechanism by which the abdominal supports are sustained affords resistance to the downward thrust of the abdominal support, which resistance becomes greater as the support is depressed 65 with the result that great weight and vigor-

ous treatment of the patient is required. In the present invention, however, as the resistance of the sustaining mechanism for the abdominal supports becomes less as the shelves are depressed, less weight need be applied with the result that the patient is more gently treated. Thus, chiropractic adjustments may be performed by practitioners with greater ease and with more comfort to the patients. 75

What I claim is:—

1. In a chiropractic table, a frame including a foot and a head pedestal spaced apart; a pair of abdominal supports in the space between the pedestals and having 80 hinged connection respectively in said pedestals; a stirrup in each of said pedestals; a prop for each abdominal support having hinged connection in the corresponding stirrup; a spring resisted toggle mechanism for 85 sustaining each of said props in normal position; and a locking means adapted to engage each of said props and hold the same in normal position.

2. In a chiropractic table, a frame; an abdominal support including a shelf hinged at one end in the frame and having a pad at the opposite end thereof; a swinging stirrup supported in the frame; a prop connected at one end with the stirrup and hinged at its 90 opposite end with the abdominal support; a toggle mechanism having sustained relation with the shelf and connected at its opposite end with the prop; and a tension mechanism for sustaining the toggle mechanism in normal position. 95

3. In a chiropractic table, a frame; a vertically movable shelf hinged at one end thereof in the frame and having a pad at its opposite end; a sternum rest hinged on 105 the frame and having limited movement thereon; means in connection with the shelf for sustaining the sternum rest when the shelf is in raised position; a stirrup hinged in the frame; a prop hinged at one end with 110 the shelf and at its opposite end with the stirrup; and a spring resisted toggle mechanism bearing against the prop and tending to hold it in normal position.

4. In a chiropractic table, having a vertically movable abdominal supporting means, a tilting sternum rest hinged upon the frame of the table; studs on the abdominal supporting means adapted to come into contact with and elevate the sternum rest as the said 115 means approaches its uppermost position; and means on the frame of the table adapted to limit the downward tilt of the sternum rest.

5. In a chiropractic table having a head 125 pedestal, a cross-piece on the rear end of the pedestal; a sternum rest hinged on the cross-piece and limited in its downward movement thereby; a head supporting member hinged at its rear end to said cross-piece; a verti- 130

5 cally adjustable prop supporting the front end of the head supporting member; and a vertically movable abdominal support having means in connection therewith for engag-
ing and elevating the sternum rest.

6. In a chiropractic table including a frame; a swinging abdominal supporting means hinged in the frame; a prop for sus-
taining said means; a swinging stirrup piv-
10 oted in the frame at one end and having connection at its opposite end with the prop;

a crank having supported relation with said means; a toggle arm on the crank having hinged connection with the prop; and a ten-
sion means having connection with the tog-
gle arm adapted to resist movement thereof. 15

In testimony whereof I affix my signature in presence of two witnesses.

ELVA BOWMAN.
